BURNHAM C. STICKNEY, OF ELIZABETH, NEW JERSEY, ASSIGNOR TO UNION TYPEWRITER COMPANY, OF JERSEY CITY, NEW JERSEY, A CORPORATION OF NEW JERSEY.

COMBINED TYPE-WRITING AND ADDING MACHINE.

No. 876,409.

Specification of Letters Patent.

Patented Jan. 14, 1908.

Application filed April 13, 1903. Serial No. 152,428.

To all whom it may concern:

Be it known that I, BURNHAM C. STICKNEY, citizen of the United States, and resident of Elizabeth, in the county of Union and State of New Jersey, have invented a certain new and useful Combined Type-Writing and Adding Machine, of which the following is a specification.

This invention relates to the class of combined writing and adding machines in which the keys which control the figure types are also used for controlling character types, and particularly to those in which a case-shift mechanism is provided for enabling either 15 set of types to be operated at will by the keys. In this class of machines the keys which control the figure types are operationally connected to the adding mechanism so as to add the amounts written by the figure types; and the object of my invention is 20 to avoid the possibility of operation of the adding mechanism when said keys are causing the character types controlled thereby to print, while enabling said keys to operate 25 the adding mechanism at the time they are causing the figure types controlled thereby to print.

One feature of my invention consists broadly in providing the case-shift mechanism (whether operated by a separate key or 30 not) with means for controlling the connection between the writing mechanism and the adding mechanism, so that when figures are being written the adding mechanism may be 35 connected to the keys, and so that when characters are being written said adding mechanism is automatically disconnected from the keys or at least rendered inoperative thereby.

My invention further consists in certain 40 features of construction and combinations of devices, all as will be fully hereinafter set forth and particularly pointed out in the concluding claims.

In the drawings forming part of this specification, Figure 1 is a longitudinal sectional elevation of a Remington No. 2 typewriting machine combined with an adding machine and embodying one form of my invention. Fig. 2 is a diagram illustrating the connections from the carriage to the adding mechanism and to the keys, and also the connections from the latter to the adding mechanism. In this diagram the upper part shows a fragmentary front elevation of the carriage, 55 and the lower part shows a plan of the keyboard of the machine.

Throughout the drawings, like signs denote like parts.

The typewriting mechanism in this instance includes a series of keys 20, carried upon the forward ends of levers 21, which are connected by links 22 to a series of type-bars 23, so as to cause the latter to strike upwardly against a platen 24 mounted upon a frame 25, which is fitted upon a carriage 26, the latter being supported in rear upon a rail 27, and in front upon a roll 28. Each of the type-bars carries a figure type 29 and a character type 30, said types being usually formed upon a single shank and carried upon a single bar. Usually the type-bars carrying the several figure types are hung side by side upon the top-plate or type-ring 31 of the machine, and each is connected by a link and lever to its key.

At Fig. 1 it will be noted that the forward or figure type 29 is indicated in dotted lines as delivering an impression upon the platen. When it is desired to operate the rear or character type 30; that is, to impress it upon the platen or the paper thereon, the platen is shifted rearwardly to the position indicated by the dotted circle 24^a; the platen frame 25 being for this purpose mounted upon the main carriage for a backward shifting movement, and provided with a forwardly extending yoke 32, which engages a shifter bar 33. The latter is carried upon upstanding rockers 34, which are connected by a rock-shaft 35, suitably journaled upon the framing; said bar, rockers and shaft together forming a shifting frame, which is operated by means of a rearwardly extending arm 36, a link 37 depending therefrom, and a lever 38 to which the lower end of said link is attached; said lever being provided at its front end with a case-shift key 39. The shifting mechanism is retained in normal position by a spring 40.

The adding mechanism is contained in a 100 casing 41, and comprises a series of adding wheels 42, which are mounted and operated in the manner set forth in the pending application of Albert H. Ellis filed November 1, 1899, Serial No. 735,449. The figure keys 20, from "1" to "9" inclusive, each operates a circuit-controller, consisting of contacts or contact plates 43 and 44. The plates 43 are electrically connected in series with one another in a circuit 45. The contact plates 44 are the respective terminals of nine wires numbered from 46 to 54 inclusive, and ex-

tending to the adding-wheel operating mechanism through a flexible cable or otherwise, for determining the extent of rotation of the number wheels.

- 5 Fixed to the paper-carriage 26 of the typewriter are a block 55 and a clamping plate 56, holding between them a series of metallic pins 57, which stand vertically and with their lower ends exposed and on a level. 10 These pins are the terminals of a series of wires 58 to 64 inclusive, also extending to the adding wheel mechanism, for selecting the number wheel which is to be turned by the operated key. A guiding rail 65 is secured 15 to the main typewriter frame, as by arms 66, secured by screws 67 to front corner-posts 68 of the framework of the typewriter, adjacent to a scale 69 mounted upon the framework, in front of which moves an index 70. Upon 20 this rail 65 is a slide 71, provided with a set screw 72, by which its position on the rail may be fixed, and carrying a finger 73 adapted to make contact with the lower ends of the pins 57, when in the traverse of the 25 paper-carriage they are carried over the finger. The slide also is provided with a short section of a scale 74, having the same divisions as the scale 69 and as many divisions as there are pins 57. The slide 71 may be 30 set at any position in front of the machine, and its position will determine at what location in the line of writing the circuits of the series 58 to 64 will be closed by the finger 73, which is the terminal of the circuit 45, the 35 latter leading through a source of power 75 to the contact plates 43 beneath the keys. 40 As usual, the carriage is provided with a letter-spacing rack 76, with which engage escapement dogs 77 and 78, carried upon a rocker 79 which is pivoted at 80 and has forwardly extending operating arms 81, from which is suspended by rods 82 a universal bar 83, arranged beneath and transversely of the key-levers 21. 45 In the operation of the foregoing mechanism, as set forth in said application, the slide or column gage 71 is adjusted along the rod 65 until the third division mark on its scale (counting from the left) is opposite the point 50 on the machine scale where the decimal point separating the dollars and cents column occurs; after operating the letter keys to write the first item on the page, the carriage is moved to the left by the operation of the 55 usual release key or spacing key until the carriage index 70 points to that division on the gage scale 74 which corresponds to the position of the first figure of the amount to be written. By reason of this adjustment of 60 the column gage, the "hundreds" adding wheel (the fifth from the left at Fig. 2) is automatically coupled to all the figure keys at that point in the line of writing at which numerals in the "hundreds" column occur. 65 Thus, if 256.74 is the amount, the index 70

will be stopped at the sixth division of the slide scale from the left, at which point the contact finger 73 will be against the fifth full line pin 57 counting from the right, thereby coupling the hundreds of dollars magnet and the corresponding wheel-controlling mechanism to all the figure keys, and simultaneously enabling any chosen key to determine the extent of rotation of the number wheel. Then the figure keys for "2," "5" and "6" 75 are struck in succession, then the period key, and then the figure keys for "7" and "4." When key for the numeral "2" is depressed, the lever 21 swings downwardly, and by means of the connecting rod 22 swings the 80 type-bar 33 having the type "2" thereon up against the paper on the platen, so that the numeral "2" is imprinted upon the paper. At the same time the universal bar 83 is carried down by the key-lever, and the initial 85 movement of the spacing dogs is effected in a well-known manner through the rods 82 and the rocker 79. The key-lever also carries down the contact plate 43, so that it touches the contact plate 44, whereby a circuit is 90 closed from the key through wire 45, battery 75, finger 73, and wire 62 to the adding mechanism, and then back through wire 46 to key "2." All of the other circuits are open at the keyboard and carriage. The closing of 95 the described circuit causes the adding mechanism to be actuated to add "2" upon the proper adding wheel. The moment the key is released, the key-lever, type-bar, universal bar and feeding dogs, as well as the contact plate 43, resume their normal positions, and the carriage moves a letter space, so that the circuit traced above is broken at two places by the rising of the key and the feeding of the paper carriage. 100

In order to avoid the possibility of operating the adding mechanism when other characters than figures are being written by means of the figure keys 20, I include in the circuit 45, which extends from the carriage to the 110 keys, a controller adapted to be operated or controlled directly or indirectly by some portion of the case-shift mechanism, preferably directly by the key-lever 38 thereof, said controller consisting of contact plates 84 and 115 85, the former being fixed upon the upper edge of the key-lever, and the latter upon the under side of a cross bar 86 of the framing. It will be seen that normally the contact is 120 closed, and that when the case shift mechanism is in normal position, the keys operate the figure types 29, as indicated in dotted lines at Fig. 1. When, however, the shift key-lever 38 is depressed, the contact between the plates 84 and 85 is broken, and 125 hence the keys 20 may be freely operated to cause the character types to print, without liability of affecting the adding mechanism. A switch 87 may be included in the circuit 45.

It will be understood that in the class of 130

machines in which each figure key controls a plurality of other characters, such as letters or punctuation marks, or arbitrary signs, in which machines the case-shift is not normally in position to cause the figure types to print, the connection between the adding mechanism and the writing mechanism would be normally broken, but would be made complete by the operation of the case-shift mechanism for causing the figure types to become operative.

While I have shown my invention as carried out in one type of electrical writing and adding machines, it will be understood that it may be applied to other types of electrical machines, as well as to those in which the writing and adding mechanisms are mechanically connected; and many changes in details of construction and operation may be made within the scope of my improvement.

Having thus described my invention, what I claim as new and desire to secure by Letters Patent, is:—

1. The combination of a writing mechanism, including a series of figure types and also including case-shifting means for rendering the figure types either operative or inoperative; an adding mechanism; and electric circuits operatively connecting said writing mechanism to said adding mechanism; said electric circuits being controlled by said case-shifting means, so as to be rendered inoperative when the figure types are inoperative.

2. The combination of a writing mechanism, including a series of figure types, a series of character types, keys each connected to both a figure type and a character type, and a case-shifting mechanism for enabling the keys to effect impressions of either figure or character types; an adding mechanism; electric circuits operatively connecting said writing mechanism to said adding mechanism; and means operatively connected to said case-shifting mechanism for controlling said circuits.

3. The combination of a carriage; a series of figure types; a series of character types; a series of keys each connected to means for operating both a figure type and a character type; case-shifting means for enabling said keys to operate either said figure types or said character types; an adding mechanism; electric connections from the adding mechanism to said carriage; electric connections from the adding mechanism to said keys; an electric connection from said carriage to said keys; and a controller in the last mentioned connection; said controller including a member connected to said case-shifting means, so as to render the adding mechanism ineffective when said keys are operating said character types.

4. The combination of a series of keys; both figure types and character types con-

trollable by said keys; a case-shifting mechanism for enabling said keys to operate either said character types or said figure types; an adding mechanism; electrical connections from the carriage to the adding mechanism; an electric connection from the carriage to the keys and including the latter in series; electric connections from the keys to the adding mechanism; and a circuit-controller having a part operatively connected to said case-shifting mechanism and adapted to render the adding mechanism inoperative whenever the shifting mechanism is operated to enable said keys to operate said character types.

5. The combination of a carriage; a series of keys; both figure types and character types controllable by said keys; a case-shifting mechanism whereby said keys are enabled to cause either said figure types or said character types to print; an adding mechanism; a series of electrical connections from the carriage to said adding mechanism; a series of controllers having parts both operatively connected to said keys and also connected in series with said carriage; an electrical connection from each of said key-operated controllers to said adding mechanism; and a controller intervening between said carriage and said key-operated controllers; said intervening controller being connected to said case-shifting mechanism so as to complete the circuit when said case-shifting mechanism is adjusted for writing figures, and to break the circuit when the case-shifting mechanism is adjusted for writing characters.

6. The combination of a writing mechanism, including a case-shift mechanism; and an adding mechanism connected to the writing mechanism through said case-shift mechanism in such a manner that the latter may make and break the connection.

7. The combination of a writing mechanism, including a series of keys and both figure types and character types controllable by said keys and also including a case-shifting mechanism for enabling said keys to operate either said figure types or said character types; an adding mechanism; connections from the writing mechanism to the adding mechanism, said connections including a part controlled by the case-shift mechanism for throwing the adding mechanism into operation when figures are printed and out of operation when characters are printed.

8. The combination of a carriage; a series of keys; both figure types and character types controllable by said keys; a case-shifting mechanism for enabling said keys to operate either said figure types or said character types; an adding mechanism; connections from said carriage to said adding mechanism; connections from said keys to said adding mechanism; and means for enabling

said case-shifting mechanism to break the connection between said adding mechanism, said keys and said carriage.

9. In a writing and adding device, the combination of a series of keys; figure types and character types controlled by said keys to print; a carriage; a case-shift device, an adding mechanism; connections whereby said adding mechanism is controlled by said keys and said carriage; and means controlled by said case-shift device for making or breaking the connection between said carriage and said adding mechanism.

10. In a writing and adding device, the combination of a series of keys; figure types and character types controllable by said keys; a carriage; a case-shift device for enabling said keys to operate either said figure types or said character types; a series of 20 adding wheels; differential mechanism for turning said adding wheels different distances according to the numbers to be added; connections between said keys and carriage and said differential mechanism; and means controlled by said case-shift device for making or breaking said connections.

11. In a writing and adding device, the combination of a series of keys; figure types and character types controllable by said keys; a carriage; a case-shift device for enabling said keys to operate either said figure types or said character types; a series of adding wheels; differential mechanism for turning said adding wheels different distances according to the numbers to be added; connections between said keys and said differential mechanism; and means controlled by said case-shift device for making or breaking said connections.

40 12. In a writing and adding device, the combination of a series of keys; figure types and character types controllable by said keys; a carriage; a case shift-device; an adding wheel; a member movable different distances according to the numbers to be added; connections between said keys and said member; and means controlled by said case-shift device for making said connections operative when numbers are printed and inoperative when characters are printed.

50 13. The combination with a double-case

typewriter having a series of figure keys and a case shift device, of a series of electrically-selected adding wheels, and a wheel-selecting electric circuit having therein a switch governed by said shift device. 55

14. The combination with a double-case key-operated mechanism having a case shift device, of an adding mechanism, and an electric circuit between said mechanisms and controlling the operation of one of said mechanisms and governed by said shift device. 60

15. The combination with a typewriting machine having shifting mechanism and an adding machine, of an electric circuit whereby an actuation of the typewriting machine may effect an operation of the adding machine, a circuit-controlling spring contact governed by the shifting mechanism to make and break the circuit. 65

70 16. The combination with a double-case typewriting mechanism having finger keys and a case-shift device, of a power-actuated adding mechanism controlled by said typewriting mechanism; and a connection between said typewriting mechanism and said adding mechanism controlled by said case-shift device. 75

17. The combination with a double-case typewriting mechanism having finger keys and a case-shift device, of an adding mechanism controlled by said typewriting mechanism; a source of power for actuating said adding mechanism; and a connection between said source of power and said adding mechanism controlled by said case-shift device. 80

85 18. The combination of typewriting mechanism including case shifting mechanism, with power driven adding mechanism controlled by the typewriting mechanism, and means controlled by the case shifting mechanism for rendering the adding mechanism operative or inoperative. 90

95 Signed at the borough of Manhattan, city of New York, in the county of New York, and State of New York, this 10th day of April A. D. 1903.
